UNITED STATES PATENT OFFICE.

ARTHUR SNELLGROVE, OF SPOKANE, WASHINGTON, ASSIGNOR, BY DIRECT AND MESNE ASSIGNMENTS, TO HIMSELF AND JEANNETTE ROCKMORE, TRUSTEES.

SANDWICH-MACHINE.

1,184,393.

Specification of Letters Patent. Patented May 23, 1916.

Application filed November 20, 1914. Serial No. 873,203.

To all whom it may concern:

Be it known that I, ARTHUR SNELLGROVE, a citizen of the United States, residing at Spokane, in the county of Spokane and 5 State of Washington, have invented certain new and useful Improvements in Sandwich-Machines; and I do hereby declare the following to be a full, clear, and exact description of the invention, such as will enable 10 others skilled in the art to which it appertains to make and use the same.

This invention relates to new and useful improvements in forms for pressing the intermediate layers of sandwiches into the 15 proper shape and to the proper thickness.

Another object of the invention is to provide a simple and effective device which will form a plurality of intermediate layers simultaneously and with a single operation.

20 A further object of the invention is to provide a novel device which may be easily and cheaply constructed and which will firmly compress the layers to prevent the same from crumbling.

25 With these and other objects in view, the invention consists in the novel combination and arrangement of parts which will be fully set forth in the following specification and accompanying drawings, in which,

30 Figure 1 is a top plan view of a sandwich maker constructed in accordance with this invention, Fig. 2 is a sectional view taken on line 2—2 of Fig. 1, Fig. 3 is a side view in elevation of a sandwich maker constructed in accordance with this invention, Fig. 4 35 is a plan view of the mold plate, Fig. 5 is a top plan view of the compressing plate, and Fig. 6 is a plan view of the knives which are used in connection with this device.

40 Referring now to the drawings by characters of reference, the numeral 1 designates the cylindrical body portion of the device which is provided at its upper terminal with the ring 2. This ring is provided at 45 spaced intervals with the upstanding hook members 3, beneath which the feet 4 of the spider, designated generally by the numeral 5, are arranged to rest. This spider comprises the arms 6 which are arranged to 50 support the collar 7 having formed cen-

trally thereof and axially therein the internally screw threaded aperture 8, the use of which will appear as the description proceeds. Supported by the ring 2 is the upstanding spring member 9 carrying 55 at its upper terminal the latch member 10, the use of which will appear as the description proceeds.

The lower end of the cylinder 1 is supported on the disk or plate 11, which is 60 provided at its periphery with the flange 12, which flange is arranged to surround the cylindrical body 1 and be soldered or otherwise secured thereto. Formed at spaced intervals on the flange are the up- 65 standing lugs 13 which are provided with central apertures through which the lag screws or bolts 14 are arranged to project. These apertures are preferably threaded and arranged to receive the shanks of the bolts 70 and the outer faces of the lugs are preferably flat to permit the legs 15 to bear thereagainst and rest firmly thereon. Extending outwardly from the plate 11 are the ears 16 having formed therein suitable apertures 17 through which the hinge pin 18 is arranged to extend. This hinge pin is arranged to form the pivotal connection for the bottom cover plate which will be more fully hereinafter described. 75

80 A suitable sleeve 19 having formed thereon a plurality of external screw threads 20, is arranged to be threaded through the internally screw threaded aperture 8 and said sleeve carries at its upper extremity the 85 squared portion 21, to which the hand wheel 22 is secured. The lower terminal of the sleeve is provided with the reduced cylindrical portion 23 which is arranged to fit the aperture 24 formed in the sleeve 25 of 90 the follower or compression plate 26. It will thus be seen that when the hand wheel is turned the follower plate 26 will press downwardly or raise upwardly according to the direction of rotation of the wheel. 95

Extending longitudinally through the axial aperture 27 of the sleeve 19 is the shaft or rod 28 carrying at its upper terminal the forked member or handle portion 29, which extends transversely with relation to the 100

longitudinal axis of the rod and terminates at its free terminals in the upstanding portions 30 which are arranged to be engaged by the latch member 10 and thereby be held 5 against rotation.

Secured to the lower end of the shaft or rod 28 is the knife designated generally by the numeral 31, which comprises the body portion 32 provided with the blade 33 having the sharpened edges 34. It will thus be 10 seen that when the handles 29 are rotated, the blades will also be caused to rotate and travel in close proximity to the upper surface of the plate 11 hereinbefore described.

The plate 11 above referred to, is also 15 provided with a plurality of spaced apertures 35, the walls of which flare downwardly as illustrated in Fig. 2 to permit the contents of the aperture to be easily removed. The walls of these openings form 20 limits for the matter from which the sandwiches are formed so as to mold said matter into the proper shape. At diametrically opposite points in the base plate these apertures are divided by the relatively wide 25 space 36. These apertures are arranged to form resting places for the blades 33 when not in use.

The lower cover plate above referred to, 30 is designated generally by the numeral 37 and comprises the disk 38 having formed upon its under side the transverse ribs 39 which terminate at their ends in the upstanding portions 40 forming the ears 35 through which the pivot pin 18, hereinbefore referred to, extends. Formed at 40 diametrically opposite points and at ninety degrees from the center of the space between the ears 40, are provided the downwardly extending ears 41, which are arranged to form pivotal connections for the lower terminals of the wire 42 which is bent to form the extensions 43 which lie parallel with the under face of the disk 38. 45 This wire 42 is bent as at 43' to form a latch member to engage the lug 44 carried by the cylindrical body 1, and said wire is again bent to form the bail 45 by means of which the operation of the door or cover 50 37 is controlled. A suitable stop member 46 which limits the rearward movement of the bail, is provided.

It will be apparent from the foregoing 55 that in use the material from which the intermediate layer of the sandwiches is to be made is placed within the cylinder 1 and upon turning the hand wheel the follower plate will be forced downwardly against the material thereby compressing the same 60 and forcing it into the apertures formed in the mold or forming plate. Due to the fact that the bottom cover plate is held upwardly by means of the bail, it will be evident that the material will be forced thereagainst and 65 after the proper amount has been forced

into the apertures the knife is rotated thereby severing the same from the main body of the compressed material, and the bail is then released from its latch member by permitting the bottom cover plate to fall carrying with it the slabs of sandwich material which are of the proper size and shape to be placed between the outer layers of the sandwich, thereby saving the time and trouble of slicing or otherwise preparing the sandwich material.

From the foregoing it will be apparent that a very simple and effective device is provided which is particularly effective in attracting attention and furnishes amusement for persons purchasing the sandwiches which are made thereby.

While in the foregoing there has been shown and described the preferred embodiment of this invention, it is to be understood that such changes may be made in the combination and arrangement of parts as will fall within the spirit and scope of the invention as defined in the appended claims.

What is claimed is:

1. A device of the character described comprising a hollow cylinder, a bottom for said cylinder provided with a plurality of annularly disposed openings, said bottom forming a mold plate, a cover plate hinged to the cylinder and engaging the under side of the mold plate, a standard extending upwardly from the mold plate, a knife secured to the lower end of the standard and engaging the upper face of the mold plate, a handle on the upper end of the standard, whereby the same may be rotated, a spider supported on the upper end of the cylinder, an internally screwthreaded sleeve centrally of the spider, a sleeve threaded into the internally screwthreaded sleeve and surrounding the standard, a compression plate at the lower end of the sleeve, a hand wheel at the upper end of the sleeve, whereby the same is rotated to move the compression plate, and means to hold the cover plate in engagement with the mold plate when the device is in use.

2. A sandwich machine comprising a bottom provided with an up turned flange on its periphery, said bottom being provided with a plurality of downwardly flared apertures, and being of a thickness sufficient to form sandwich fillers of a desired size, an open ended cylinder mounted on the bottom and held in place by the up turned flange, a cover plate hinged to one side of the bottom and forming an end wall, flared openings to limit the movement of the material pressed into the opening, a compression plate operable within the cylinder, a support at the upper end of the cylinder and connected to the cylinder, a screw threaded stem on the compression plate and operable

through the support so that upon rotation of the stem the compression plate will be forced toward the bottom, a knife operable over the upper face of the bottom, and a standard extending through the screw threaded stem and adapted to be rotated to actuate the knife and sever the material compressed in the apertures in the bottom

from the bulk of the material within the cylinder.

In testimony whereof I affix my signature in presence of two witnesses.

ARTHUR SNELLGROVE.
